UNITED STATES PATENT OFFICE.

FRANK O. HOAGLAND, OF HARTFORD, CONNECTICUT, ASSIGNOR TO PRATT & WHITNEY COMPANY, OF NEW YORK, N. Y., A CORPORATION OF NEW JERSEY.

BARREL-REAMER.

1,323,278.

Specification of Letters Patent.

Patented Dec. 2, 1919.

Application filed June 8, 1917. Serial No. 173,439.

To all whom it may concern:

Be it known that I, FRANK O. HOAGLAND, a citizen of the United States, residing at Hartford, in the county of Hartford and 5 State of Connecticut, have invented certain new and useful Improvements in Barrel-Ramers, of which the following is a specification.

The invention relates particularly to 10 reamers adapted to be used in long or deep holes such as those in rifle barrels. Heretofore considerable difficulty has been encountered in doing work of this class. There has been a marked tendency for the reamers 15 to grip or adhere to the sides of the bore and become broken, and even when this did not happen there was difficulty in removing the chips from the several cutting edges which were provided. Furthermore, only 20 a very small amount of metal could be removed at a single operation, and when it was necessary to remove larger amounts of metal several successive operations were necessary.

25 The principal object of the invention is to provide an improved reamer suited for operation in long or deep holes and adapted to remove a relatively large amount of metal without encountering difficulties such as 30 those above referred to.

In the accompanying drawing I have shown several embodiments of the invention in order that the scope and application thereof may be clearly perceived. It will be 35 understood, however, that the drawing is intended to be merely illustrative and is not intended to define or limit the scope of the invention, the accompanying claims being relied upon for that purpose.

40 Figure 1 is a side view of a reamer embodying the invention.

Fig. 2 is a side view similar to Fig. 1 but showing a different embodiment of the invention.

45 Fig. 3 is another view similar to Fig. 1 but showing a still different embodiment of the invention.

Fig. 4 is an end view, on a greatly enlarged scale, of the reamer shown in Fig. 1, 50 the view being taken from the left.

Fig. 5 is a transverse sectional view on the same scale as Fig. 4 showing an embodiment of the invention different from that shown in Fig. 4. This view can be understood as 55 being taken along the line $b-b$ of Fig. 1.

The drawing shows reamers adapted for reaming relatively small holes, but it is to be understood that the invention is not so limited and that with suitable modifications it is possible to construct larger reamers embodying the invention. 60

Referring first to Figs. 1 and 4 of the drawing, A represents the main cutting section of the reamer. This section is tapered, increasing in diameter from the plane $a-a$ 65 to the plane $b-b$. The taper is greatly exaggerated in the drawing in order that it may clearly appear. In practice, however, in a reamer such as is used for reaming rifle barrels, the taper may be between three 70 and four one-hundredths of an inch. Adjacent the section A is a section B which preferably tapers very slightly in the direction opposite to that of the section A. The taper is greatly exaggerated in the drawing 75 in order that it may clearly appear, but in practice for reamers of the class above referred to, the taper may be as little as one one-thousandth of an inch.

A sector of approximately 90° is removed 80 from the sections A and B to form a longitudinal groove 1. At one edge of this groove is the single cutting edge 2 with which the reamer is provided.

In reamers as heretofore constructed, a 85 great deal of difficulty has been encountered because of the tendency of the outer walls of the reamer to grip or adhere to the surface of the bore. I avoid all such difficulties by relieving the outer wall of the reamer 90 in such a way that it contacts with the surface of the bore only at the cutting edge 2 and at a point 3 which is nearly opposite the cutting edge. Preferably, as shown in Fig. 4, the point 3 is located a little less than 95 180° from the cutting edge 2. The location of the point 3 a little less than 180° from the cutting edge 2 makes it possible for the reamer to be firmly supported and guided by the wall of the bore. If the point of tangency 3 were exactly opposite the cutting edge there might be a tendency for a wedging action which would produce chattering and uneven cutting. The wall of the reamer from the cutting edge 2 to the point 100 105 3 conforms to smooth curves which touch the wall of the bore at 2 and 3. The curves begin to deviate from the respective cutting circles immediately behind the cutting edge. By the cutting circles I mean the circles 110

which are followed by the several points along the cutting edge, these circles conforming, or approximately conforming, to the outline of the bore. From the point 3 to 5 the point 4 at the side of the notch opposite to the cutting edge the curves are continued and lie within the outline of the bore. It will be understood that the amount of relief is considerably exaggerated in Fig. 4 in order that it may be clearly seen. In practice, the amount of relief will ordinarily be but a few thousandths of an inch.

As concerns the broader features of my invention, I do not limit myself to any particular form of curve for the outer wall of the reamer, but I prefer to form the outer wall, at least between the points 2 and 3, in the form of spirals which are constructed about a center 5 eccentric of the center of 10 the bore, designated by 6. The center 5 is located on the diameter which passes through the point 2 and is on the opposite side of the center 6. As illustrated in Fig. 4, the center 5 is so positioned that the 15 spirals constructed about it have points of tangency with the cutting circles and with the outline of the bore at 3. As shown in this figure, the spirals are continued beyond the point 3 and terminate at 4.

30 It will be seen that when relative turning is effected in the direction of the arrow in Fig. 4, the cutting edge 2 will be forced along the surface of the bore and the reamer will be held in central relationship to the 35 bore by reason of the engagement between the wall of the reamer and the surface of the bore at 3. At all other points the wall of the reamer and the surface of the bore are out of engagement, thus making it impossible for 40 the reamer to bind or adhere. Preferably, as shown in Fig. 1, the cutting edge 2 is notched at 2^a so as to break up the chips which are removed.

Any one of several constructions may be 45 provided for controlling and driving the sections A and B of the reamer. As shown in Fig. 1, the reamer is provided with a pilot or plug section C which has a diameter slightly greater than the smallest diameter 50 of the section A. This pilot section C is very slightly smaller than the original diameter of the hole to be reamed and assists in guiding the reamer and in holding it central. The pilot section C is connected with 55 the section A through an intermediate neck section D of reduced diameter. Connected with the section C is a driving stem E by means of which the reamer is operated. For 60 supplying oil to the groove 1 and to the cutting edge 2 there is provided a central oil hole 7 which extends through the stem E and the pilot C and intersects the groove 1 at 8. As illustrated, the groove 1 is closed at one end adjacent the point of communication 65 with the oil hole 7. In practice the

stem E is connected with a suitable tube or hollow rod, the connection usually being made by brazing. The central aperture of the tube registers with the hole 7 and at the other end of the tube suitable means are provided for supplying oil under high pressure. 70

Relative rotative movement is effected between the reamer and the device to be reamed, and in the case of a rifle barrel the reaming is usually effected by means of a 75 machine which holds the barrel against rotative movement and which rotates the reamer relatively thereto. In operation, therefore, it may be considered that the reamer is rotated. At the same time relative feeding 80 movement is effected to carry the reamer deeper into the bore. Usually the reamer is held against longitudinal movement and the barrel is fed. In the case of the construction shown in Fig. 1, the movement of the 85 barrel is toward the right as indicated, and the bore is enlarged to a diameter equal to that of the reamer at b—b.

During operation, oil under high pressure is supplied through the hole 7 and 90 enters the groove 1 through the opening at 8. The plug section C prevents the oil from flowing back toward the left.

The oil which enters the groove 1 serves not only to lubricate the cutting edge and 95 to provide a film of oil between the wall of the reamer and the surface of the bore, but also serves to carry away the chips which are removed by the cutting edge 2. This latter function of the oil is very important 100 as it prevents the reamer from becoming clogged. With earlier constructions having a plurality of cutting edges and a plurality of grooves, much difficulty was encountered because of the tendency for one or more of 105 the grooves to become clogged, the oil flowing out through the remaining grooves. As soon as any one groove became even partially clogged the flow of oil through that groove was immediately lessened, thus automatically increasing the clogging. The result was that in earlier reamers all but one or two of the grooves were clogged very quickly after the cutting operation started. 110 With my improved reamer the oil must necessarily flow through the one groove which is provided, and any possible clogging is entirely prevented. 115

The form of the reamer shown in Fig. 1 is known as a "pull" reamer, but my invention is equally well adapted to be embodied in a "push" reamer. Such a reamer is shown in Fig. 2. This reamer comprises sections A' and B' which are similar respectively to the sections A and B of the reamer shown in Fig. 1. A groove 1' extends longitudinally of these sections but terminates a short distance from the left-hand end of the section B'. A cutting edge 2' is provided at one side of the groove 1' and the 120 125 130

sections A' and B' are relieved in the way already described. I prefer not to provide a pilot section such as is shown in Fig. 1. This is not needed to direct the oil and I find that without it the reamer will in many cases cut more accurately. A stem E' is connected with the left-hand end of the section B' and is provided with an oil hole 7' which communicates with the groove 1' at 8'.

This reamer operates in the same way as the reamer shown in Fig. 1 except that the relative feeding movement is in the opposite direction, the rifle barrel being fed toward the left as indicated. The chips are forced out of the groove 1' in advance of the reamer instead of behind it.

In Fig. 3 I have shown a reamer adapted for hand use or for use in a turret lathe. This comprises sections A' and B' similar respectively to the sections A and B of the reamer shown in Fig. 2. This reamer is provided with a longitudinal groove 1' similar to the groove 1, and at 2'' there is provided a cutting edge similar to the cutting edge 2'. The sections A'' and B'' are relieved in the way already described. Connected with the left-hand end of the section B'' is a shank E'' by means of which the reamer may be rotated or held against rotation as required. It will be obvious that means may be added for supplying oil if needed.

Under some circumstances it may be desirable to provide a form of relief slightly different from that already described and shown in Fig. 4. This is illustrated in Fig. 5, which may be considered to be a cross section taken along the line b—b of Fig. 1. The form of relief differs from that shown in Fig. 4 in that the wall of the reamer from the point 3 to the point 4 conforms to circular arcs constructed about the center 5. It will be noted that because of the eccentricity of the center 5 the circular arcs between 3 and 4 lie within the outline of the bore. This construction is preferable in some cases as it provides a smaller clearance between the wall of the reamer near the point 4 and the adjacent part of the surface of the bore. It will be understood that between the points 2 and 3 there will be a film of oil extending from the point 2 to the point 3, and that there will be a similar film of oil extending from the point 3 to the point 4. In some cases, when the construction shown in Fig. 4 is used, the opening between the point 4 and the wall of the bore will be too great to be filled by an oil film. In such cases I prefer to provide the construction shown in

Fig. 5 in order to reduce the width of this 60 opening.

What I claim is:

1. A reamer having a single cutting edge and a relieved outer wall extending backward in smooth curves from the cutting edge 65 to points of tangency to the cutting circles nearly opposite the cutting edge.

2. A reamer having a single cutting edge and a relieved outer wall extending backward in smooth curves from the cutting edge 70 to points of tangency to the cutting circles a little less than 180° from the cutting edge.

3. A reamer having a single cutting edge and a smoothly curved outer wall which touches the cutting circles at the cutting 75 edge and which is tangent to the said circles at points nearly opposite the cutting edge and which is elsewhere relieved.

4. A reamer having a single cutting edge and an outer wall conforming to spirals constructed about a center eccentric of the cutting circles and extending from the cutting edge at least to points nearly opposite thereto, the said outer wall having points of tangency with the cutting circles. 80

5. A reamer having a single cutting edge and a relieved outer wall extending backward in spiral curves from the cutting edge to points of tangency to the cutting circles nearly opposite the cutting edge. 85

6. A reamer having a single cutting edge and an outer wall partly conforming to spirals constructed about a center eccentric of the cutting circles and partly conforming to circular arcs constructed about the 95 said eccentric center.

7. A reamer comprising a single piece of metal approximately circular in general transverse sectional outline and having a sector of approximately 90° removed to provide a single cutting edge, the outer wall being relieved to provide points of intersection with the cutting circles at the cutting edge and at points of tangency to the cutting circles nearly opposite the cutting edge. 100

8. A reamer approximately circular in general transverse sectional outline and having a longitudinal sectoral groove which provides a single cutting edge and a central longitudinal oil hole at one end which communicates with the sectoral groove, the reamer being provided at the last said end with a plug section which prevents the escape of oil at that end. 110

In testimony whereof I hereto affix my 115 signature.

FRANK O. HOAGLAND.
